UNITED STATES PATENT OFFICE

154,190

DESIGN FOR A CURTAIN

Leonard Singer, New York, N. Y.

Application February 3, 1948, Serial No. 144,227

Term of patent 14 years

(Cl. D47—6)

To all whom it may concern:

Be it known that I, Leonard Singer, a citizen of the United States of America, residing in New York city, county of New York, and State of New York, have invented a new, original, and ornamental Design for a Curtain, of which the following is a specification, reference being had to the accompanying drawing, forming part thereof, wherein,

Figure 1 is a front elevational view of a curtain showing my new design.

Figure 2 is an enlarged fragmentary view of a row of the diagonally arranged pleated trim on the body of the curtain.

Figure 3 is an enlarged fragmentary view of the edge ruffle trim.

I claim:

The ornamental design for a curtain, substantially as shown.

LEONARD SINGER.
